UNITED STATES PATENT OFFICE.

JOHN KRUFT, OF WEST HOBOKEN, NEW JERSEY, ASSIGNOR TO OSCAR SCHMIDT, OF JERSEY CITY, NEW JERSEY.

NOTE PROJECTION.

SPECIFICATION forming part of Letters Patent No. 674,208, dated May 14, 1901.

Application filed February 19, 1901. Serial No. 47,952. (No model.)

To all whom it may concern:

Be it known that I, JOHN KRUFT, a subject of the Emperor of Germany, and a resident of West Hoboken, in the county of Hudson and State of New Jersey, have invented a new and Improved Note Projection, of which the following is a full, clear, and exact description.

The invention relates to note sheets or barrels for mechanical musical instruments; and its object is to provide a new and improved note projection which is exceedingly strong and durable and not liable to bend or break off when the note sheet or barrel is in use in the instrument.

15 The invention consists of novel features and parts and combinations of the same, as will be fully described hereinafter and then pointed out in the claims.

A practical embodiment of the invention is 20 represented in the accompanying drawings, forming a part of this specification, in which similar characters of reference indicate corresponding parts in all the views.

Figure 1 is an enlarged plan view of the 25 blank for forming the note projection. Fig. 2 is an enlarged plan view of the improvement. Fig. 3 is a sectional side elevation of the same on the line 3 3 in Fig. 2. Fig. 4 is a rear perspective view of the same, and Fig. 30 5 is a front perspective view of the same.

The note projection is struck up from and 35 forms an integral part of a sheet A, of metal or other suitable material, and said note projection consists, essentially, of a tongue B and a brace C. The tongue B is rectangular in shape and extends approximately at a right angle to the sheet A, as is plainly indicated in the drawings, while the brace C is struck up from a blank rhomboidal in shape

40 and located at one side of the tongue B, said brace having its body portion C' integral with the sheet A and the bent-over portion C² standing approximately at a right angle to the body portion and lying flat against the back of the tongue B, as is plainly indicated in the drawings, to brace said tongue B and hold the same against bending or breaking off when the note sheet or barrel is in use in a musical instrument. It is understood that 45 50 the rhomboidal blank for the brace is bent

up from the sheet, and then the corner portion C² is bent at a right angle to the body portion of the blank to produce the brace, which has its body portion arranged lengthwise in the direction of the movement of the tongue B, the bent-over portion C² being parallel with and in contact with the tongue B. By this arrangement an exceedingly strong and durable note projection is produced, especially as the material of the sheet immediately at the rear of the base of the tongue B is not disturbed—that is, is not cut out, as is the case with many note projections heretofore produced.

It is understood that by forming the brace 65 from material of the sheet A, located at one side of the tongue B, it is evident that the individual strength of the tongue is not impaired in the least, but the tongue itself is reinforced or braced by the bent-over portion 70 C² of the brace C.

Having thus fully described my invention, I claim as new and desire to secure by Letters Patent—

1. A note projection, consisting of a tongue 75 struck up from a sheet, and a brace struck up from the sheet independently of the tongue at one side thereof, the brace having a bent-over portion lying against the back of the tongue, as set forth. 80

2. A note projection, consisting of a tongue struck up from a sheet and rectangular in shape, and a brace struck up from the sheet at one side of the tongue, the blank of the brace being rhomboidal in shape and the brace having a corner portion bent at a right angle to its body, the corner portion lying flat against the back of the tongue, as set forth. 85

3. A note projection, consisting of a tongue struck up from a sheet and rectangular in shape, and a brace struck up from the sheet at one side of the tongue, the blank of the brace being rhomboidal in shape and the brace having a corner portion bent at a right angle to its body, the corner portion lying flat against the back of the tongue, and the body portion of the brace extending at a right angle to the tongue at one side thereof, as set forth. 95 100

4. A brace for the tongue of a note projection, struck up from a sheet independent and at one side of the tongue, the brace having a body portion integrally connected with the sheet, and a bent portion extending approximately at a right angle to the body portion and parallel with the tongue, to engage the back thereof, as set forth.

5. A blank for a note projection, consisting of a rectangular tongue, and a rhomboidal

brace located at one side of said tongue, as set forth.

In testimony whereof I have signed my name to this specification in the presence of two subscribing witnesses.

JOHN KRUFT.
